US00D782972S

(12) **United States Design Patent** (10) **Patent No.:** **US D782,972 S**
(45) **Date of Patent:** **** Apr. 4, 2017**

(54) **DETACHABLE POWER SUPPLY FOR DATA LOGGER**

(71) Applicant: **Fluke Corporation**, Everett, WA (US)

(72) Inventors: **Ferdinand Y. Laurino**, Seattle, WA (US); **Matthew Bannister**, Lake Stevens, WA (US)

(73) Assignee: **Fluke Corporation**, Everett, WA (US)

(**) Term: **14 Years**

(21) Appl. No.: **29/523,201**

(22) Filed: **Apr. 7, 2015**

Related U.S. Application Data

(62) Division of application No. 29/441,514, filed on Jan. 7, 2013, now Pat. No. Des. 726,647.

CLAIM

The ornamental design for a detachable power supply for data logger, as shown and described.

DESCRIPTION

FIG. 1 is a front top perspective view of a detachable power supply for data logger.

FIG. 2 is a front bottom perspective view thereof.

FIG. 3 is a back bottom perspective view thereof.

FIG. 4 is a back elevation view thereof.

FIG. 5 is a front elevation view thereof.

FIG. 6 is a top plan view thereof.

FIG. 7 is a bottom plan view thereof.

FIG. 8 is a right side elevation view thereof; and,

FIG. 9 is a left side elevation view thereof.

The broken lines in the drawings illustrate portions of the detachable power supply for data logger that form no part of the claimed design.

1 Claim, 7 Drawing Sheets
